UNITED STATES PATENT OFFICE

BENTLEY A. PLIMPTON, OF BALTIMORE, MARYLAND, ASSIGNOR TO LOCKE INSULATOR CORPORATION, OF BALTIMORE, MARYLAND, A CORPORATION OF MARYLAND

CONDUCTOR SUSPENSION CLAMP

Application filed February 25, 1927. Serial No. 170,926.

This invention relates to clamping devices used for suspending conductors from insulators.

The principal object of the invention, generally stated, is to provide a suspension clamp which may be manufactured very simply and cheaply and yet be capable of giving as efficient service as those of more expensive design.

10 An important object of the invention is to provide a suspension clamp formed in a peculiar manner to provide an adequate bearing seat to which is clamped a conductor engaging keeper, said seat or saddle portion 15 being struck out from the sides of the body portion, the entire device, aside from the keeper member, being capable of being formed from a single piece of sheet metal stamped or cut and pressed to possess the desired configuration.

Yet another object of the invention is to provide a suspension clamp embodying a keeper or relatively movable clamping element and a U-bolt, the keeper member having portions thereon cooperating with the bolt to prevent longitudinal displacement, said portions being in the nature of lugs straddling the sides of the bolt and these lugs being capable of engagement with the side 30 of the clamp when load is applied whereby to increase the slip strength of the clamp and make it possible to employ a U-bolt of comparatively small size.

To the attainment of the foregoing and other objects and advantages the invention preferably consists in the detailed structure and the arrangement and combination of parts to be hereinafter more fully described and claimed, and illustrated in the accompanying drawing in which:

Figure 1 is a side elevation of a clamp constructed in accordance with the invention;

Figure 2 is a horizontal section taken on the line 2-2 of Figure 1, and

45 Figure 3 is a central vertical cross section taken on the line 3-3 of Figure 2.

Referring more particularly to the drawing, I have shown the clamp as comprising a relatively stationary member 1 and a relatively movable member or keeper 2. The member

1 is preferably of curved shape throughout and is substantially U-shaped in cross section in that it includes a channel-like bottom portion 3 and upstanding side portions 4 which are formed with openings 5 for the reception of suspension means such as a hook or the like located at the bottom of a string of insulators or other support. The bottom wall or portion 3 of the member 1 is not only curved transversely throughout the major portion of its length but is also longitudinally curved to provide flaring ends 6 which permit a certain play in the conductor 7 without it coming in contact with the edges of the ends, it being well understood that chafing or other wear at these points should be strictly avoided as being injurious to the conductor.

Formed at the center of the bottom portion 3 is a base, seat or saddle portion 8 which is preferably flat and which is defined partly by lateral projections 9 stamped or struck out from the sides 4 when the openings 5 are formed therein. In the formation of this base or saddle portion by striking out a portion of the metal left when the openings 5 are formed, the material of the sides is pressed out adjacent the openings 5 as shown at 10, the material at these points merging into the lateral extensions 9.

The conductor 7 of course lies upon the curved bottom portion 3 and the flat central base or saddle portion 8 of the member 1, and clamping is effected by means of a preferably elongated relatively movable member or keeper 11 which is preferably concavo-convex in cross section with its concave side engaging the conductor.

In addition to the above described parts, the device includes a U-bolt 12 which passes through suitable holes in the base or saddle portion 8 and which has its arms provided with nuts 13 engaging against the underside of the saddle portion. The U-bolt embracingly engages and extends transversely above the keeper member 11 so as to cause it to exert the proper clamping action upon the conductor. To prevent longitudinal displacement of the keeper member with respect to the relatively stationary portion of the

clamp, the keeper is shown as provided at opposite sides with lugs 14 notched at 15 for the accommodation of the arms of the U-bolt.

In the actual manufacture, the device may 5 be made from a flat blank which is stamped or cut to give it the proper contour and to define the openings 5. The material at these openings 5 is not all removed as sufficient is left and pressed out to define the lateral extensions 9 which form the base or saddle portion through which the U-bolt extends when installation is made. After the preliminary cutting or other shaping, the blank is folded longitudinally and pressed by means of suitable dies to give it the longitudinal curvature 10 and the proper shape in other respects. The bulging of the material outwardly at the sides of the openings 5 to permit it to merge into the lateral extensions 9 will increase the 15 strength and rigidity of the clamp.

The device is of course installed and used in the same manner as any other clamp for the same purpose. When heavy strain comes upon it it is possible that there will be a tendency for the sides to draw toward each other 20 and if this should occur it is clear that they may engage against the opposite edges of the keeper member 11 and assist the clamping action thereof. If a conductor of sufficiently 25 large diameter be clamped by the device, the lugs 14 may possibly engage against the inner faces of the sides 4. It will be noted that owing to the provision of the notched lugs at the side edges of the keeper there will be 30 no possibility of longitudinal displacement of the keeper with respect to the relatively stationary portion of the device and the holding action will therefore at all times be assured. Inasmuch as the device is formed 35 principally from a single sheet metal blank and as it may be constructed or shaped by folding or pressing it is evident that its manufacture will be a simple and inexpensive proposition. It is really believed that the 40 construction, operation and advantages will be readily apparent to one skilled in the art 45 without further explanation.

While I have shown and described the preferred embodiment of the invention and the 50 detailed method steps involved in its production, it should be understood that the right is reserved to make any and all such changes as will not depart from the spirit of the invention or the scope of the appended claims.

Having thus described the invention, I 55 claim:

1. In a device of the character described, a relatively stationary member of elongated shape substantially U-shaped in cross section 60 and having a transversely and longitudinally curved bottom portion and spaced parallel upstanding side portions, said side portions being formed with opposite openings, the central portion of the bottom being formed 65 with lateral extensions at the lower ends of

said openings, said lateral extensions being formed with holes, a keeper member located between the sides and cooperating with the bottom of the relatively stationary member to constitute clamping means, and a U-bolt straddling said keeper member and having its arms passing through said holes and equipped with nuts. 70

2. In a clamp of the character described, an elongated relatively stationary member substantially U-shaped in cross section and including a longitudinally and transversely curved bottom portion and spaced parallel sides merging therewith, said sides being formed with openings for the reception of a suspension element, a portion of the material left in forming said openings being struck out to define lateral extensions merging into said bottom and into the sides, said lateral extensions defining a central saddle portion, 80 said saddle portion being formed with spaced holes, a keeper member located between said sides and formed at its opposite edges with notched lugs, and a U-bolt straddling said keeper member and passing through said holes with its ends equipped with nuts, said notches accommodating said bolt. 90

3. In a device of the character described, a relatively stationary member of elongated shape substantially U-shaped in cross section 95 and having a transversely and longitudinally curved bottom portion and spaced parallel upstanding side portions, said side portions being formed with opposite openings, the central portion of the bottom being formed 100 with lateral extensions at the lower ends of said openings, said lateral extensions being formed with holes, a keeper member located between the sides and cooperating with the bottom of the relatively stationary member to constitute a clamping means, and a U-bolt straddling said keeper member and having its arms passing through said holes and equipped with nuts, said keeper member having notched portions at its sides accommodating 105 said bolt.

4. In a device of the character described, a relatively stationary member including a curved bottom portion and spaced sides merging therewith and provided centrally with 110 elongated openings adapted to receive a suspension element, said relatively stationary member being provided at the bottom with lateral projections formed from the material struck out in the formation of said openings, said lateral extensions and the portion of the bottom therebetween constituting a central flat saddle portion, the material at the sides of the openings being bulged outwardly and merging into said lateral extensions, a keeper member cooperating with said bottom, and bolt means engaging the keeper member and passing through said saddle portion for effecting a clamping relation. 115

5. The method of making the relatively sta- 120

- tionary portion of a suspension clamp, comprising cutting a blank, forming the blank at opposite sides of its center with elongated openings, folding the blank longitudinally to define spaced parallel side portions connected by a curved bight portion, and striking out a portion of the materials at the adjacent ends of said openings to define extensions projecting laterally beyond said sides to form a central relatively flat saddle portion. 10
6. In a conductor suspension clamp, a body substantially U-shaped in vertical cross section having its bottom adapted to support a conductor and having sides formed with openings, the body having lateral extensions at said openings, a keeper member located between the sides and cooperating with said bottom to constitute clamping means, and a bolt embracing the keeper member and said extensions. 15
7. In a suspension clamp, an elongated body substantially U-shaped in vertical cross section and including a bottom portion adapted to support a conductor and further including spaced sides having openings, a lateral extension on the body opposite the opening in the side thereof, a keeper member located within the body and cooperating with the bottom thereof to constitute clamping means, and a bolt engaging the keeper member and passing through said extension. 20
8. In a device of the character described, an elongated body including a bottom portion and spaced sides having openings therein and formed with lateral extensions at the openings, a keeper member located between the sides and having laterally extending portions located within the openings, and bolt means embracing the keeper member and passing through said first named lateral extensions. 25
9. In a device of the character described, an elongated body including a bottom portion and spaced sides having openings therein and formed with lateral extensions at the openings, a keeper member located between the sides and having laterally extending portions located within the openings, and bolt means embracing the keeper member and passing through said first named lateral extensions, said last named lateral extensions being notched to accommodate the bolt. 30
10. In a suspension clamp, an elongated body including a bottom portion and spaced sides formed with opposite openings, a keeper member enclosed within the body, and bolt means within the openings embracing the keeper member and passing through the bottom portion of the body. 35
- 60 11. In a device of the character described, a body including a bottom portion and spaced upstanding sides having openings therein, a keeper member enclosed within the body and having projections received within the openings, and bolt means located within the open- 40
- ings and embracing the keeper member and connected with the bottom portion of the body. 45
